CLAIM

The ornamental design for a body for writing instrument, as shown and described.

DESCRIPTION

FIG. 1 is a front perspective view of a body for writing instrument showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The evenly spaced broken lines in the figures depict portions of the body for writing instrument which form no part of claimed design.

The dot-dash broken lines in the figures represent a boundary line and form no part of the claimed design.

1 Claim, 6 Drawing Sheets
